UNITED STATES PATENT OFFICE

EARL J. VALLEN, OF AKRON, OHIO

REMOTE CONTROL MECHANISM

Application filed May 22, 1928. Serial No. 279,781.

The present invention relates particularly to the operation of curtains, either of the vertically or horizontally moving type, garage or auditorium doors and similar devices in which the curtain or door is movable by electrical motors of the reversible type. The object of the invention is to improve upon the starting mechanism by means of which the switch governing the operation and movement of the motor is positively and accurately controlled.

Advantages and objects of the invention will be understood from the detailed description of the apparatus and its method of operation. One of the particular objects of the invention is to provide a more positive operating mechanism for the switch and to prevent accidents in the movement of the curtain. The device comprises a rotating switch which is controlled by a single push or snap button, the mechanism providing for full and complete control over the mechanism by the operation of a single switch. The apparatus also includes a positive circuit opening device operable by the position of the moving parts so that the curtain or door can not go past its normal limits in either direction.

While the device is shown and described in considerable detail so that all of the parts of the mechanism will be clearly understood, it is not the intention to limit the invention to exact conformity with the details as illustrated, variations and modifications being permissible within the scope of the invention as set forth in the claims. It will also be understood that the invention may be applied to other arts and purposes within the scope thereof.

In the drawings:

Figure 1 is a general assembly of the complete curtain operating mechanism including the curtain moving devices and the switch mechanism;

Figure 2 is a top plan view of the switch;

Figure 3 is a front elevation;

Figure 4 is a section on the line 4—4 of Figure 3;

Figure 5 is a section on the line 5—5 of Figure 4;

Figure 6 is a section on the line 6—6 of

Figure 5, showing the way in which the safety device operates to prevent accidental reversing of the curtain before the mechanical stopping devices can be brought into action; and

Figure 7 is a wiring diagram for the apparatus.

The operating mechanism complete is mounted upon a substantially L-shaped base 1, upon one portion of which is mounted a housing 2 for the motor to drive the curtain. Upon the other portion of the base is secured a pan 3 in which is mounted the bracket 4 for supporting the switch or control mechanism for the motor.

A motor is indicated at 6, the shaft 7 of the motor having a worm 8 which drives a worm gear 9 on the curtain operating shaft 10. The shaft extends through the housing and at one side thereof supports a pulley 11 which is driven through a spring clutch 12, actuated by spring 13, so that if the curtain sticks or jams in its travel, the motor will be saved. Double pulleys 15 are mounted above the pulley 11, being supported upon a stub shaft 16 in the upper end of an arm 18 extending upwardly from the housing. The curtain operating cable 19 is trained over the pulleys as is understood by those skilled in this art.

The shaft 10 is provided with a worm 20 which operates a small worm gear 21 on a rotating turning shaft 22. This shaft is provided with two adjustable dogs 23 and 24 which are designed to wipe against the inside of a curved shoe 25 on the upper end of a lever 26 which may be yieldingly held to the right by a tension spring 28 and which is pivoted on the housing at 27. The dogs are adjusted at the proper positions about the slowly rotating shaft 22 to throw the switch automatically at the limits of the curtain movement, as will be described in that portion of the specification relating to the switch.

The current to the motor is delivered through the wiring system in Figure 7 from the main lines 30, the direction of the motor being determined by the position of a rotating switch indicated at 32. This switch is com-

posed of a drum of insulating material having a pair of contact bars 33 secured to the face of the drum, each bar comprising long arms 34 and short arms 35 placed on diametrically opposed points on the drum and connected by bridge pieces 36, the long and short arms of each bar being placed in opposition to one another. The several zones of the switch are separated by flanges or rings 38 and on each side of the switch are mounted 5 spring brushes 40 arranged in groups of three, as shown in Figures 2 and 7, to make the required circuits for operating the motor in reverse directions, as shown by the wiring diagram.

10 The drum switch has periods of movement of 90° so that the brushes make and break the required circuits, the motor being successively started, stopped, started in reverse direction and stopped, as the drum is rotated, 15 the brushes resting against the side of the drum when the motor is not running.

The drum is designed to be operated, step by step, by two mechanisms, by the operative or by the positive throw-off actuated by either 20 the dog 23 or 24. The mechanism for actuating the drum under control of the operator is operated by a push button 42 placed at a convenient point for the operator, additional 25 push buttons being provided at convenient 30 points about the stage, if desired. The push button 42 opens and closes the auxiliary circuit 43 from the main line to a solenoid or magnet 45 which is secured to the bracket 4 adjacent the drum switch. The core or 35 armature for the solenoid is indicated at 46 and is pivoted at its lower end to a link 48 which is in turn pivoted to a swinging arm 49 extending from a hub 50 which is rotatable 40 about the axis of transverse shaft 51 on which the drum switch is mounted, the shaft being secured at its ends in the bracket 4.

From the hub 50 extends a second arm 52 from which depends a pawl 53 moved inward- 45 ly by the spring 54. The pawl 53 engages a four-toothed ratchet disk 55, each tooth of the ratchet corresponding to a point of rest of the drum switch. The ratchet disk is secured to a sleeve 56 rotatable upon the shaft 51 and extending through the hub 50, being provided upon its outer end with a 180° double spiral cam face 58. This cam face engages and mates with a similar cam face 59 on a sleeve 60 slidable on the shaft 51, but 55 prevented from rotation thereon by pin 61 which is passed through the shaft and projects through opposed slots 62 in the sleeve.

The sleeve 60 carries a fixed ratchet 65 and is normally held in mating relation with 60 the sleeve 56 by a coil spring 66 which surrounds the sleeve 60 and bears against the pin 61 and against the side of the four-toothed ratchet 65.

Secured to the base of the bracket 4 is a 65 U-shaped guiding plate 70, one arm of which

is provided with an inturned lug 71 which lies in the path of the teeth on the ratchet 65 when the ratchet is moved to the right as viewed in Figure 3. When, however, the sleeve 56 is rotated through the solenoid 70 and ratchet, the rotation of the cam face 58 over the cam face 59 forces the sleeve 60 outwardly until the ratchet tooth clears the lug 71, whereupon the shaft 51 can rotate.

The drum switch is connected to the shaft 75 by a transverse pin 75 which also secures a sleeve 76, the end of which projects beyond the drum and is connected to one end of a coil spring 77, the other end of which is connected to the ratchet 55.

80 The operation of the mechanism which has been described may be briefly summarized. When the solenoid is energized, the core 46 is elevated which, through the pawl 53, moves the ratchet 55. The movement of 85 the ratchet will wind up the spring 77 and at the same time force the sleeve 60 outwardly. Energy will be stored in the spring until the ratchet 65 clears the lug 71, whereupon the force in the spring will throw the 90 switch drum a quarter revolution, being stopped by the engagement of the next ratchet tooth on the ratchet 65 with the lug 71 and the parts will reassume their normal position. The contact brushes have been 95 moved to their next position either in or out of contact with the conductor bars. By momentarily closing the circuit, the operator controls the movement of the curtain, stopping or starting it at will. Upon a single 100 operation of the push button 42, the curtain can be in turn started, stopped or started in reverse direction. If the operator wishes to move the curtain in the same direction after stopping, three rapid operations of the 105 push button will give the desired result.

In order to prevent backward movement of the drum switch, a spring-actuated pawl 80 is mounted in the path of the ratchet 55.

In order to connect the switch with the 110 mechanical or positive stop at the limits of the curtain movement by the dogs 23 and 24, means are provided to move the drum switch to off position. In order to accomplish this result, the lower end of the lever 26 is pivoted 115 to a horizontal push bar 82, the outer end of which is yieldingly held upwardly by a spring 83 and is slidable in notches 84 in the plate 70. The movement of the push bar is limited by pins 85 which contact with the 120 vertical walls of the guiding plate. In that portion of the push bar within the guiding plate is located a notch 86 which registers with a two toothed ratchet 88 secured to the sleeve 56. When either dog 23 or 24 wipes 125 against the shoe, the push bar is moved outwardly and the wall of the notch 86 engages one of the teeth of the ratchet 88 to move it to the dotted line position of Figure 6, thus actuating the drum switch in the same man- 130

ner the switch is operated by the solenoid to stop the motor and thus the movement of the curtain. It will be apparent that only two teeth are needed on this ratchet as the kick-off operated by the dogs is operative only while the curtain is moving. When the motor is stopped the dog which has moved the lever 26 and the push bar 82 to throw the drum switch will still be engaged with the shoe 25, thus holding the lever 26 and the push bar 82 to the left against the action of the tension spring 28. At this time, the thicker portion of the push bar is beneath the ratchet and in contact with the rounding portion thereof as seen by the dotted line position of Figure 6. In this position the switch can be thrown one step only by the solenoid to the full line position of Figure 6. It cannot be given a second movement by the solenoid until the operating dog passes back off the shoe which allows the spring 28 to pull the bar 82 back to the position of Figure 4. This is for the reason that the upper side of the push bar is in the path of the ratchet 88 so that it engages the flat side of the bar after the movement to the full line position.

In this manner one of the dogs 23 or 24, shoe 25, lever 26 and bar 82 act to automatically stop the motor and the curtain at the end of its travel in either direction. As above described the solenoid 45 can at this time only be operated once which tumbles the drum switch and reverses the motor and the direction of travel of the curtain and which moves the operating dog back off the shoe 25 to allow the bar 82 to resume its normal position, at which time the solenoid 45 can again be operated as desired to stop, start or reverse the travel of the curtain. As soon, however, as one of the dogs engages with the cam shoe 25 to move the push bar 82 to throw the drum switch and stop the motor, the solenoid can only be operated once which reverses the motor as will be understood. This mechanism insures that the curtain will always be stopped at the end of its travel in either direction regardless of the acts of the operator.

It will be observed that a highly efficient and practicable curtain operating mechanism has been devised which will operate satisfactorily at all times and cannot get out of order. The action of the rotating switch is positive and effective. There is no possibility of the switch occupying an intermediate or inoperative position and the mechanical or positive "kick off" insures against injury to the curtain through inexperienced curtain operators. The operator can control the curtain in its opening or closing movements, and secure any movement desired with a single push button. In the claims where a "curtain operating mechanism" is referred to, it will be understood that the term is not necessarily limited to theatre or auditorium curtains, but

doors or partitions are intended to be included. It will also be understood that the term "solenoid" is intended to cover magnetic moving means of all kinds which may be substituted for the solenoid shown and described.

What is claimed is:

1. A mechanism for controlling a reversible motor, comprising a switch, and means for moving the switch to on or off position comprising a solenoid, a circuit breaking mechanism adapted to be operated at a predetermined limit of the movement of a mechanism operated by the motor and means to prevent operation of the switch by the solenoid to 75 actuate said mechanism in the direction in which it moves to said limit until the circuit breaking mechanism is restored to its normal position.

2. A mechanism for controlling a reversible motor, comprising a rotating switch, and means for moving the switch through a portion of its rotation comprising a solenoid, connections from the solenoid to the switch, a circuit breaking mechanism also operable 80 upon the switch and adapted to be controlled by mechanism operated by the motor at limits of movement of said mechanism, and means to prevent operation of the switch by the solenoid so as not to actuate said mechanisms beyond said limits until the circuit breaking mechanism is restored to its normal position.

3. A mechanism for controlling a motor, 100 said mechanism including a drum switch, a solenoid, a ratchet mechanism operable by the solenoid, a stop device actuated by the limit of movement of mechanism operated by the motor, and connections from the stop device to the drum switch, said connections including a detent to prevent premature operation of the switch by the solenoid.

4. A mechanism for controlling a motor, comprising a drum switch, said drum switch having on and off positions, a solenoid and ratchet mechanism to move the drum switch to on and off positions successively, a mechanical device to move the drum switch to off position only, and means operated by the mechanical device to prevent movement of the 115 drum by the solenoid to off position.

5. A mechanism for controlling a motor and a device actuated thereby, comprising a drum switch, said drum switch having on and off positions, a solenoid and ratchet mechanism to move the drum switch to on and off positions successively, a mechanical device to move the drum switch to off position only, and means operated by the mechanical device to prevent movement of the drum by 120 the solenoid to off position, said last means being operative only at a period near a limit of movement of the device actuated by said motor.

6. In a device for controlling a motor, a 130

drum switch, two ratchets rotatable with respect to the drum, a spring connected to the drum and adapted to be placed under tension by movement of the ratchets, a detent to hold the drum until the spring is placed under tension, means to release the detent at the end of movement of the ratchets, and independent mechanisms to operate the ratchets, one of said mechanisms being electrically controlled and the other mechanically controlled.

7. In a device for controlling a motor, mechanism operated thereby, a drum switch, two ratchets rotatable with respect to the drum, a spring connected to the drum and adapted to be placed under tension by movement of the ratchets, a detent to hold the drum until the spring is placed under tension, means to release the detent at the end of movement of the ratchets, and independent mechanism to operate the ratchets, one of said mechanisms being controlled by the operator at will and the other controlled positively by limitations of the mechanism operated by the motor.
